RENEWABLE HEEL

Newton W. Doane, San Francisco, Calif.

Application September 13, 1944, Serial No. 553,896

1 Claim. (Cl. 36—36)

The invention relates to footwear and more especially to a renewable heel therefor.

The primary object of the invention is the provision of a heel of this character, wherein the section thereof having the greatest wear is readily and conveniently removed for replacement of a new section at the tread of such heel, and this section is such that it can be made fast in place without the use of pegs, nails, screws or the like, or in other words it does not require tackings for such purpose.

Another object of the invention is the provision of a heel of this character, wherein the renewable area thereof can be made from plies of fibrous materials having increased wearing qualities, thereby giving maximum life wear to such heel, the renewable section being of novel and unique construction.

A further object of the invention is the provision of a heel of this character, wherein the renewable section thereof is self latching for the firm and secure fastening of the same in place on the heel, and is susceptible of convenient detachment when required.

A still further object of the invention is the provision of a heel of this character, which is simple in construction, thoroughly reliable and effective in purpose, strong, durable, readily and easily attached and detached, and inexpensive to manufacture and install.

With these and other objects in view the invention consists in the features of construction, combination and arrangement of parts as will be hereinafter more fully described, illustrated in the accompanying drawing, which shows the preferred embodiment of the invention, and pointed out in the claims hereunto appended.

In the accompanying drawing:

Figure 1 is a fragmentary side view of an article of footwear showing the heel constructed in accordance with the invention applied.

Figure 2 is a perspective view of the heel detached and looking toward its bottom.

Figure 3 is a view similar to Figure 2 showing the renewable section detached.

Figure 4 is a vertical longitudinal sectional view through the heel.

Figure 5 is a bottom plan view of the heel showing by dotted lines the interfitting of the renewable section.

Figure 6 is a perspective view of the renewable section looking toward its innermost face.

Similar reference characters indicate corresponding parts throughout the several views in the drawing.

Referring to the drawing in detail A designates generally a portion of an article of footwear, which may be of any standard construction, and B denotes the heel thereof constructed in accordance with the invention.

The heel B comprises a permanent heel body 10, which has a renewable tread section 11 which is preferably of segment formation congruous with a countersunk seat 12 provided in the body 10 and opening through the rear and side edges thereof to effect an inner step 13 therein. The section 11 and the step 13 are interlocked by a tongue and groove overlapping joint 14 therebetween at the said step and edge of the section next to each other.

The heel body 10 is permanently fastened in place on the footwear A by fasteners 14, while the section 11 is renewable and is snap fastened in the seat, this being effected by the dove-tailed shape inwardly tapering key-formation 15 on the inner face of such section 11, which is located at the rear edge thereof. The key formation 15 is insertable in a correspondingly shaped key-way 16 provided in the ceiling 17 of the seat 12 and opening through the rearmost edge of the body 10 for wedge-like sliding action in such seat.

The outer face of this key formation is provided with a centrally located inwardly sloping latching nib 18 for the firm and secure fastening of the section 11 in the seat, yet such section can be detached when the occasion requires, especially on the wearing away of the same through use thereof, the said section being pried from the seat for renewal of such section. This nib 18 is designed to enter a holding notch 19 therefor in the key-way 16, and the section 11 requires no other fastening for holding it in place in the seat 12 in the heel B. The nib 18 is inherently compressible in kind.

What is claimed is:

A heel of the kind described, comprising a permanent body having a countersunk seat opening through the rear thereof, a renewable section for the seat, and having its forward portion interlocked with the body, releasable dove-tailed shaped connections between the body and section and a latching nib included with said connections.

NEWTON W. DOANE,
